Primary Examiner — Selina Sikder(74) *Attorney, Agent, or Firm* — Womble Bond Dickinson (US) LLP(57) **CLAIM**

We claim the ornamental design for a garage door opener, as shown and described.

DESCRIPTION

FIG. 1 is a front bottom perspective view of a first embodiment of our new design;

FIG. 2 is a bottom view thereof;

FIG. 3 is a front view thereof;

FIG. 4 is a right side view thereof;

FIG. 5 is a rear view thereof;

FIG. 6 is a left side view thereof; and

FIG. 7 is a top view thereof.

FIG. 8 is a front bottom perspective view of a second embodiment of our new design;

FIG. 9 is a bottom view thereof;

FIG. 10 is a front view thereof;

FIG. 11 is a right side view thereof;

FIG. 12 is a rear view thereof;

FIG. 13 is a left side view thereof; and,

FIG. 14 is a top view thereof.

The views of the garage door opener not shown form no part of the claimed design. The dash-dot lines in the figures show optional features and environmental elements that form no part of the claimed design. The dash-dot lines in FIGS. 5, 7, 12, and 14 define boundaries of the claimed design that form no part thereof.
